UNITED STATES PATENT OFFICE.

LAURENCE J. BERKELEY, OF RACINE, WISCONSIN, ASSIGNOR TO THE P & M COMPANY, OF CHICAGO, ILLINOIS, A CORPORATION OF ILLINOIS.

RAIL-ANCHOR.

1,303,237.

Specification of Letters Patent. Patented May 13, 1919.

Application filed July 30, 1918. Serial No. 247,404.

To all whom it may concern:

Be it known that I, LAURENCE J. BERKELEY, a citizen of the United States, residing at Racine, in the county of Racine and 5 State of Wisconsin, have invented certain new and useful Improvements in Rail-Anchors, of which the following is a specification.

My invention relates to a device for preventing the longitudinal movement or creep 10 of railroad rails, and particularly to an anchor or anti-creeping device adapted to be applied to one flange only of the rail.

One of the principal objects of the invention 15 is to provide an anti-creeping device of this type which, although light in weight, compact of structure and convenient to manipulate, will have great capacity for gripping the rail and the requisite strength to 20 withstand the heavy stresses to which an anti-creeping device is subjected in service. A more particular object of the invention is to provide a rail anchor or anti-creeping device of the type indicated consisting of a 25 single rail engaging member which may be made of sheet metal, and a simple key or wedge for effecting a permanent engagement of said member with the rail.

The invention consists of the novel arrangements and devices to be hereinafter 30 described and claimed for carrying out the above stated objects and such other incidental objects as will appear from the following description of the preferred embodiment 35 of the invention shown in the drawings appended hereto, wherein—

Figure 1 is a fragmentary side elevation of a rail and cross tie showing the anchor applied to the rail.

Fig. 2 is a plan view of the parts shown in Fig. 1.

Fig. 3 is a sectional view on line 3—3 of Fig. 1; certain parts of the device being shown in elevation for the purpose of 45 clearness.

Fig. 4 is a perspective view of the rail engaging member of the anchor.

Fig. 5 is a plan view of the cut and punched blank from which the body of 50 the anchor is formed, and

Fig. 6 is a perspective view of the key utilized for effecting a locked engagement between the anchor and rail.

Like characters of reference designate like 55 parts in the several figures of the drawings.

In the drawings it will be seen that the device is applied to one flange 10 of the rail in such position as to abut one of the ties 11 which support the rail.

The rail engaging member or body of 60 the anchor is formed, in the preferred embodiment of the invention, from a blank, shown in Fig. 5, the portion 12 of the blank being bent downwardly on the line 13 to form a depending brace or leg. The portion 65 14 of the blank is bent upwardly approximately along the line 15, and is adapted to form the upper jaw which overlies the flange of the rail. This portion, and also the intermediate portion 16, are preferably 70 pressed to provide stiffening ribs 17, 18, which extend around the bend which is formed on the line 15. The portion 19 is bent downwardly and is adapted to lie against the tie, while the portion 20 is bent 75 on the line 21 and forms a brace or leg parallel with the leg 12. The portions 12, 20 are cut and bent to form short tongues 22, 23 defined by lines 24, 25 of Fig. 5. These tongues, when bent as shown in Fig. 3, form 80 ledges or shelves for a key 26. The intermediate strip 16 is cut to provide a tongue 27, which is given a set downwardly when the device is manufactured and is provided in any suitable manner, for example, by punching or pressing, with sharp projections or 85 teeth 28 designed to engage the base of the rail. The extremity 29 of the tongue 27 is bent downwardly and sharpened for engagement with the upper edge of the key 26. 90

The key 26 in applying the device to the rail is driven through the openings in the legs 20, 12 and forces the projections 28 on the tongue 27 into the bottom of the rail base. The down turned edge of the tongue 95 bites into the key so that there is an interlocking of the parts of the anchor as well as a locked engagement of the anchor to the rail which insures great capacity for resisting creeping stresses.

If the base part 16 is formed with ribs 18, as shown, the leg 20 is notched at 30 to fit these ribs. The meeting edges of the several parts of the rail engaging member of the anchor may be welded together, if 105 found expedient, but ordinarily this will not be necessary.

It is apparent that, without departing from the principle of the invention, certain modifications may be made in the design of 110

the anchor, depending, for example, upon the kind of metal employed and other considerations. The use of a casting, for instance, in place of sheet metal for the body 5 of the anchor would necessitate making the tongue, which has to be resilient, of a separate piece. Other modifications will suggest themselves to those familiar with this art.

I claim:

10. 1. A rail anchor comprising a rail engaging member provided with a tongue adapted to bite into the rail at a point within the vertical edges thereof, and a wedge for forcing said tongue into engagement with the rail.
15. 2. A rail anchor comprising a rail engaging member provided with a flexible tongue adapted to bite into the rail at a point within the vertical edges thereof, and a wedge for forcing said tongue into engagement with the rail.
20. 3. In a rail anchor, the combination of a sheet metal element bent to form flange embracing jaws and a depending tie abutting structure; a tongue adapted to have a biting engagement with the base flange of the rail at a point within the vertical edges thereof, and means for forcing said tongue into engagement with the rail base.
25. 4. In a rail anchor, the combination of a pair of jaws adapted to engage with one flange of a rail, a toothed tongue movable in an aperture in said jaws, and a key adapted to engage said toothed tongue and to force the same into biting engagement with the base of the rail.
30. 5. A built-up rail anchor comprising a plate bent to form a pair of jaws, a depending tie-abutting flange and depending bracing flanges, a toothed tongue formed in one of said jaws, said brace flanges being formed with apertures, and a key adapted to extend through said apertures and engage said tongue to force the teeth thereof into engagement with the rail base.
35. 6. A rail anchor comprising a blank bent to form a pair of stiffened jaws, and a box-like depending structure, one of said jaws having a tongue provided with sharpened projections, the box-like structure being formed with apertures, and a key to extend through said apertures for engaging said tongue and causing the projections thereon to engage with the base of the rail.
40. 7. A rail anchor comprising a blank bent to form rail engaging jaws, a pair of depending bracing flanges having apertures therein, and means providing a locking engagement between the aforesaid structure and the rail comprising a key adapted to be driven through said apertures.
45. 8. A rail anchor comprising a blank bent to form rail engaging jaws, a pair of depending bracing flanges having apertures therein, means providing a locking engage-

ment between the aforesaid structure and the rail comprising a key adapted to be driven through said apertures, and a toothed tongue engaged by said key.

9. A rail anchor comprising a plate bent 70 to form rail engaging jaws, a pair of depending bracing flanges, the lower jaw being slit to form a tongue, the bracing flanges being slit to form tongues which are bent at right angles to provide a slideway for a key, 75 and a key adapted to be driven into said slideway to engage said tongue and force the same against the rail base.

10. A rail anchor formed from a plate bent to provide jaws adapted to engage the 80 rail base, and an underlying box-like structure consisting of a tie-abutting flange, and bracing flanges at opposite sides of the tie abutting flange, said bracing webs having registering apertures for the accommodation 85 of a key, said lower jaw member being slit to provide a tongue adapted to be engaged by a key in said apertures; and a key to force said tongue into engagement with the rail base. 90

11. A rail anchor for engagement with one side only of a rail comprising a jaw to engage one edge of the base flange of the rail, a tongue adapted to have a biting engagement with the rail base, a key to force 95 the tongue against the rail, and an apertured structure providing a bearing for the key.

12. A rail anchor for engagement with one side only of a rail comprising a jaw to engage one edge of the base flange of the 100 rail, a tongue adapted to have a biting engagement with the rail base, a key to force the tongue against the rail, and a depending apertured structure adapted to lie against a tie and providing a bearing for the key. 105

13. A rail anchor for engagement with one side only of a rail comprising a jaw to engage one edge of the base flange of the rail, a tongue adapted to have a biting engagement with the rail base, a key to force 110 the tongue against the rail, and a depending structure adapted to bear against a tie apertured and provided with supporting ledges for said key.

14. A rail anchor for engagement with 115 one side only of a rail comprising a jaw to embrace one edge of the base flange of a rail, a tongue to engage the rail base, a key to force said tongue against the rail, and an apertured structure providing a bearing for the key, said tongue being formed so as to have a biting engagement with the rail and with the key. 120

15. A rail anchor comprising a sheet metal blank cut and bent to form a rail engaging 125 jaw, a tie abutting flange comprising flanges at right angles to the tie abutting flange which are formed with apertures, and a resilient tongue on the under side of the jaw in combination with a key adapted to be 130

driven through said apertures so as to force said tongue against the rail base.

16. A rail anchor comprising a sheet metal blank cut and bent to form a rail engaging jaw, a tie abutting flange comprising flanges at right angles to the tie abutting flange which are formed with apertures, and a resilient tongue on the under side of the jaw

in combination with a key adapted to be driven through said apertures so as to force said tongue against the rail base, said tongue being formed with teeth adapted to bite into the rail and its outer edge being turned down to engage the key.

LAURENCE J. BERKELEY.
